MEANS FOR VENTING CORE BOXES

Henry L. Demmler, Kewanee, Ill.

Application April 29, 1937; Serial No. 139,646

5. Claims. (Cl. 22—13)

My invention relates to molds or core boxes to be used in connection with mold or core making machines of the type in which a mold or core box is clamped against a sand container from which sand is forced into the mold or core box by compressed air.

An object of my invention is to provide an improved means for venting the compressed air passing into a mold or core box, and also the atmospheric air which is present in an empty mold or core box, and at the same time to prevent the escape from the mold or core box of the sand which is forced thereinto.

Another object is to provide venting means for core boxes which is less liable to become clogged by particles of sand than are the venting means now in use.

Another object is to provide venting means for core boxes which can be more easily cleaned of obstructing particles of sand than are the venting means now used.

Another object is to provide venting means for core boxes which are more efficient and have a greater capacity than do the venting means now in use.

Another object is to provide an inexpensive venting means for core boxes which is more durable and longer-lived than the venting means now used.

30 Other objects and advantages will become apparent as the description proceeds.

In the drawing:

Figure 1 is a vertical sectional view, somewhat diagrammatic, of a core box embodying my invention, in position in a core making machine;

Figure 2 is a view of an inside wall of a core box incorporating one embodiment of my invention;

Figure 3 is a section taken on the line 3—3 of Figure 2;

40 Figure 4 is a bottom view of the structure shown in Figure 3;

Figure 5 is a sectional view, similar to Figure 3, but showing a modified form of my invention; and

Figure 6 is a sectional view, similar to Figure 3, but showing another modified form of my invention.

Referring to the drawing, I have illustrated in Figure 1 a machine comprising a frame 1 which supports a pressure head 2 and a sand container 3. The sand container 3 will be understood that the upper end of the sand container is closed, and is provided with piping or other suitable means for supplying compressed air or other pressure fluid thereto. The sand container 3 is further provided with a removable bottom plate 4, provided with a central

aperture 5 through which the sand is forced into the mold or core box 6.

This mold or core box 6 is shown as supported on bars 7 resting upon the pressure head 2, which is in the form of a cylinder slidably mounted on a stationary piston 8. The piston 8 has a vertical bore 9 communicating with a pipe 10 connected with a source of compressed air or other pressure fluid, whereby fluid under pressure may be admitted to the space between the piston 8 and cylinder 2 to force the mold or core box 6 firmly against the bottom plate 4 of the sand container 3.

It will be understood that the mold or core box 6 may be of any desired size or shape, and that the number and arrangement of the venting means will depend upon the size and shape of the mold or core box. The particular mold or core box shown may be considered as illustrative only, and is provided with a laterally extending projection 11 provided with my improved venting means, indicated generally at 12. Similar venting means 12 are also indicated as being provided in the bottom of the box. These venting means 12 may be of any of the three types disclosed in this application.

The particular type of venting means shown in Figures 2, 3 and 4 comprises a tapered outer sleeve 13 which has a drive or press fit with a wall of the mold or core box 6, it being understood that the term "wall" is used generically to cover a side, bottom or top part of the box, or any projection or extension thereof. This sleeve 13 has a generally cup-shaped recess 14 formed in its inner end, and this cup-shaped recess communicates with a plurality of bores 15 arranged in the form of a circle about an enlarged central bore 16 which may be threaded as indicated at 17.

As best shown in Figure 3, the central bore 16 and most of the cup-shaped recess 14 are filled by a central member 18 having a threaded stem 19 which coacts with the threads 17 of the sleeve 13 to secure the member and sleeve together. The member 18 has a tapered upper end 20 terminating in an edge 21 which cooperates with the adjacent edge 22 of the sleeve 13 to provide a metered annular slot 23 of such size that air can pass therethrough but sand cannot.

The inner surface 24 of the member 18 is flat, and lies in the same plane as the inner end 25 of the sleeve 13 and the inner surface 26 of the adjacent wall of the mold or core box 6. It will be understood that where a fine grade of sand is used, the annular slot 23 must be quite small to prevent the passage of sand therethrough, whereas when a coarser quality of sand is used, a

wider slot may be used without permitting the sand to pass therethrough. I therefore make my venting means adaptable to different qualities of sand by making the member 18 removable and replaceable by a different member having a larger or smaller inner end, so that by providing a plurality of members 18 of different sizes, the mold or core box may be readily adapted for use with different sands. Where the member 18 is 5 screwed into the sleeve 13 as shown in Figure 3, the inner end of the member 18 is preferably provided with a kerf 27 for receiving the end of a screw driver to be used in unscrewing the member 18 from its sleeve 13. This removal and replacement can be accomplished without removing the sleeve 13 from the mold or core box.

It is important that no projections or depressions be provided on the inner surface of the mold or core box, but that this box have a smooth 20 inner surface exposed to the sand. I therefore find it desirable to fill the kerf 27 with rubber or other suitable material 28 which can easily be removed from the kerf 27 by means of a sharp tool when it is desired to unscrew the member 18.

25 The sleeve 13 and member 18 have their inner ends exposed to the blast of sand entering the mold or core box through the orifice 5, and are thereby subject to a grinding or abrasive action. I therefore prefer to make the sleeve 13 and the 30 member 18 of steel or other suitable wear resisting material, and I prefer to harden the inner ends of the sleeve 13 and member 18 to increase their wear resisting properties. In some instances it is advisable to harden the entire sleeve and the 35 entire member rather than their inner ends only.

While the width of the annular slot 23 is less than the diameter of the grains of sand used in the mold or core box, the annular slot in its entirety provides a relatively large opening through 40 which the air may freely escape from the interior of the mold or core box. The air passing through the slot 23 passes between the upper end of the sleeve 13 and the enlarged head of the member 18, and thence through the bores 15 to atmosphere. It will be noted that the taper 20 of the 45 enlarged end of the member 18 provides for the free escape of any particles of sand which may pass through the slot 23, and thereby reduces the likelihood of clogging.

50 I have found that a slot of a given width and a length several times its width is much less likely to clog than is a circular orifice having a diameter equal to the width of the slot. Such a slot is therefore far superior to a plurality of such circular orifices having the same theoretical venting capacity. Furthermore, it is much easier to remove any particles of sand which may become wedged in such a slot than it is to remove particles of sand becoming wedged in such circular 55 orifices.

The embodiment shown in Figure 5 is identical with that shown in Figures 2, 3, and 4, except that in the embodiment of Figure 5 the member 18—A and outer sleeve 13—A have a press fit instead of being screwed together as in Figures 2, 3, and 4.

Where the member is press-fitted into its sleeve, it is unnecessary to provide the member with a kerf such as the kerf 27 of the embodiment of 70 Figure 3.

In the embodiment of Figure 6, greater venting capacity is provided in a small area, and this form of my invention is particularly desirable where it is essential to provide the maximum venting capacity in a small cavity or corner formed in the 75

wall of the mold or core box. In this form of my invention I provide an outer sleeve 30 which is press-fitted into the wall of the mold or core box, as in the previous embodiments. The inner end 5 of this sleeve 30 is provided with a large cup-shaped recess 31 which communicates with a plurality of bores 32 arranged in the form of a circle about a large central bore 33.

An inner sleeve 34 is threadedly or otherwise secured in the bore 33 and has an enlarged inner 10 end 35 providing an edge 36 cooperating with the adjacent edge 37 on the outer sleeve to form an annular slot 38, through which the air may escape but which is too small to permit the passage of sand therethrough. The inner end of the inner sleeve 34 is likewise provided with a cup-shaped recess 39 communicating with a plurality of bores 40 arranged in the form of a circle about a central bore 41. A member 42 is threadedly or otherwise secured in the bore 41 and has an enlarged inner 20 end 43 providing an edge 44 which cooperates with the adjacent edge 45 on the inner sleeve to provide a second annular slot 46 for the escape of air. This slot likewise is too narrow to permit the escape of sand therethrough.

25 It will be understood that where the member 42 is threadedly secured in the inner sleeve 34, this member 42 is provided with a kerf 47 which may be filled with rubber or other suitable material 48. The inner sleeve 35 may also be provided with holes 49 for receiving the prongs of a tool used in unscrewing this inner sleeve from the outer sleeve 30. These holes 49 may likewise be filled with rubber or other suitable material so that a smooth 30 surface is provided for contact with the sand in 35 the mold or core box.

It is to be understood that my invention is not limited to the particular form shown in the drawing, and that the scope of my invention is to be limited solely by the following claims.

I claim:

1. Venting means of the class described, comprising a box, a sleeve press fitted thereto, said sleeve having a circular recess communicating with a central bore and a plurality of bores grouped about said central bore, a second sleeve located in said central bore and having cooperation with an end of said first named sleeve to provide an annular slot for permitting passage of air therethrough but for preventing passage of sand therethrough, said second sleeve having a circular recess communicating with a central bore and a plurality of bores grouped about said central bore, and a member located in said last named central bore, said member having an end located in said last named recess and cooperating with an end of said second sleeve to provide a second annular slot adapted to permit passage of air therethrough but adapted to prevent passage of sand therethrough.

2. Venting means of the class described comprising a wall member having an aperture therein providing an enlarged portion opening upon a side of said wall member along a well defined edge of predetermined dimensions about a predetermined axis, a second member disposed in said enlarged portion having an end face and a tapering circumferential face centrally located with respect to said enlarged portion, said tapering face intersecting said end face along a second well defined 70 edge having dimensions corresponding with and slightly less than said first dimensions to provide a clearance between said edges to permit the passage of air therethrough exclusive of core sand, means for securing said members axially 75

relative to each other, and means for connecting said enlarged portion to atmosphere.

5 3. Vent means of the class described comprising a wall having an aperture therein defining a surface of revolution and providing an enlarged portion opening upon the inside of said wall along a well defined marginal edge and an internally threaded reduced portion opening into said enlarged portion, means for venting said enlarged portion to the atmosphere independently of said reduced portion, and a headed member having a marginally well defined end face threadedly received in said reduced portion to a depth whereby said end face is approximately flush with said wall and the marginal edge of said end face is closely proximate to the marginal edge of said enlarged portion to permit the passage of air therebetween exclusive of core sand, the headed portion adjacent said enlarged portion having a circumferential face defining a second surface of revolution inclined to said first surface of revolution whereby the clearance between said headed member and said enlarged portion is relieved behind said marginal edges.

10 15 20 25 4. Venting means of the class described comprising a wall member having a compartment on a side thereof bounded by a well defined edge

of a predetermined contour, a second member disposed in said compartment having a tapering face of a cross-sectional contour similar to said first contour, said contours being slightly different as regards their corresponding dimensions to provide a clearance permitting passage of air between said members exclusive of core sand granules of a predetermined size, means for moving one member relative to the other to vary the amount to said clearance, and means for venting said compartment to atmosphere.

5 10 15 20 25 5. Venting means of the class described comprising a sleeve, a second sleeve disposed in said first sleeve with sufficient clearance therebetween to provide a restricted slot permitting passage of air therethrough to the exclusion of core sand, and a member disposed in said second sleeve with sufficient clearance between said member and said second sleeve to provide a second restricted slot permitting passage of air therethrough to the exclusion of core sand, means for detachably securing said sleeves together and said members to said second member, and means for venting said slot to the atmosphere.
